DESIGN FOR AN AUTOMATIC SHOESHINE MACHINE

Carl Bader, St. Louis, Mo.

Application January 22, 1949, Serial No. 407

Term of patent 14 years

(Cl. D9—2)

To all whom it may concern:

Be it known that I, Carl Bader, a citizen of the United States and a resident of St. Louis County, State of Missouri, have invented a new, original, and ornamental Design for an Automatic Shoeshine Machine, of which the following is a specification, reference being had to the accompanying drawing, forming part thereof.

Fig. 1 is a plan view of an automatic shoeshine machine, showing my new design,

Fig. 2 is an elevational view looking at the front of the machine,

Fig. 3 is an elevational view looking at the side of the machine and,

Fig. 4 is a perspective view looking at the side opposite that shown in Fig. 3.

I claim:

The ornamental design for an automatic shoeshine machine, substantially as shown.

CARL BADER.
